Des 854

12-23-1856

Dec. 854

Garrison Smith & H. Brown of Philad^a Pa.
Letters Patent No. 854 Dated Dec. 23rd 1836

The Schedule referred to in these Letters Patent
and making part of the same.

To all whom it may concern:

Be it known, that
we, Garrison Smith, and Henry Brown, of the
City and County of Philadelphia and State
of Pennsylvania, have produced a new and
original design for cook stove: designated as the
"Young American," and we do hereby declare that
the following is a full, clear and exact de-
scription of the said design, reference being had
to the annexed drawing, forming part of this

specification, in which

Figure 1 is a side elevation of the stove,

Figure 2 is a front elevation of same,

Figure 3 is an elevation of foot.

Similar characters of reference in the several figures denote the same part of stove and design.

The side plate A bears two panels B and C; the former constituting the oven door, and ornamented in bas-relief by a figure composed of a tablet a, central figure b, foliage c, and scrolls d, arranged and having the configuration shown in the drawing. The panel C bears an ornament composed of tablet e, figure f, scrolls g and foliage h, arranged and configured as shown in fig 1.

The side plate, above the panels B and C, flares outward and upward, and is embellished by the wavy ornament i, and projections k, arranged as shown in fig 1. Below the panels is the inscription "Patented 1856" in raised capitals and numerals.

The front of the stove has the doors D and E, the former ornamented with foliage l, arranged and configured as shown in fig 2. The doors E have each an ornament F in bas-relief, made up of tablet m, figure n, foliage p, and scrolls q, arranged and having the configuration set forth in fig 2.

The front plate Q has a forward swell given by the reeded corners r, r, terminating at top in cap s, upon which is foliage t. Between the doors D and E is a tablet bearing the inscription "Young American" in raised capitals.

The foot T is embellished by the foliage w. issuing from the middle thereof and embracing the globular projection x. The lower portion terminates in a paw. The details of the whole are as shown in fig 3.

We claim as a new and original stove design of our own production

The design, configuration and arrangement of the ornaments in bas relief on the several plates as above set forth and delineated in the drawing, constituting stove design "Young American"

In testimony whereof, we have hereunto signed our names before two subscribing witnesses.
